UNITED STATES PATENT OFFICE.

JAMES A. LYNCH, OF SALT LAKE CITY, UTAH.

BEET DUMP.

Application filed November 14, 1921. Serial No. 515,015.

To all whom it may concern:

Be it known that I, JAMES A. LYNCH, a citizen of the United States, residing at Salt Lake City, in the county of Salt Lake 5 and State of Utah, have invented a new and useful Beet Dump, of which the following is a specification.

This invention relates to an apparatus especially designed for handling beets, the 10 primary object of the invention being to provide endless conveyors for loading beets into cars or the like for transporting the same to refineries.

Another object of the invention is to provide means for feeding beets directly onto the endless conveyor, eliminating the necessity of providing separate feeders for accomplishing this result.

A still further object of the invention is 20 to provide means for separating foreign matter from the beets during the passage of the beets from the endless conveyors.

Another object of the invention is to provide agitating means for agitating the beets 25 on their passage over the endless conveyor to insure the foreign matter being separated from the beets.

With the foregoing and other objects in view which will appear as the description 30 proceeds, the invention resides in the combination and arrangement of parts and in the details of construction hereinafter described and claimed, it being understood that changes in the precise embodiment of 35 the invention herein disclosed, may be made within the scope of what is claimed, without departing from the spirit of the invention.

Referring to the drawings:—

Figure 1 is a side elevational view of a 40 beet handling apparatus constructed in accordance with the present invention.

Figure 2 is a plan view of the same.

Figure 3 is a fragmental enlarged detail 45 view of the cleaning section of the beet handling apparatus.

Figure 4 is a sectional view taken on line 4—4 of Figure 1.

Figure 5 is a sectional view taken on line 5—5 of Figure 3.

50 Figure 6 is a sectional view taken on line 6—6 of Figure 3.

Referring to the drawings in detail, the reference character 5 designates a suitable unloading platform which is supported as

by means of the posts 6 and disposed over 55 the pit 7. Supported above the platform 5 is a frame work 8 which embodies an upper horizontal bar 9, and angularly disposed bracing bars 10, the bar 9 providing a support for the pulleys 11 over which the cable 12 moves during the operation of dumping 60 a wagon body. At one end of the cable 12 is a hook member 13 which is designed to be positioned in the link member 14 carried by the movable wagon body 15.

A hopper 16 has its upper extremity disposed in proximity to the wagon which is positioned on the unloading platform, so that when the body 15 thereof is tilted, the beets contained in the body 15 will fall into 70 the hopper 16. The lower extremity of the hopper 16 lies over the lower portion of the endless conveyor 17 and houses the upper portion thereof, so that the beets delivered into the hopper will be directed to the end- 75 less conveyor 17.

This endless conveyor operates over the idle rollers 18 which are supported within the conveyor frame 19 which is formed in any suitable manner and provided with inclined boards 19' which have their lower ends disposed in spaced relation with the side edges of the conveyor and arranged directly thereover, as clearly shown by Figure 4 of the drawings. These boards 19' extend 85 along the outer edges of the frame and prevent the beets that move with the conveyor, from passing laterally therefrom.

The lower end of the conveyor is disposed in the pit 7, while the upper end 90 thereof is disposed in a plane so elevated that the upper end of the conveyor will lie in proximity to a car or similar loading device, to receive material therefrom. Supported by the conveyor frame at the respective ends thereof are the rollers 20 and 21, the roller 20 being supported in suitable adjustable bearings so that the conveyor may be taut at all times.

Mounted at one end of the roller 21 is a 100 sprocket wheel 22 which receives motion from the power device, through the chain 23, pinion 24 and gear 25 which receives motion from the power device 26 as through means of the belt 27, pulley 28 and pinion 29. 105

The conveyor frame is supported at its outer end by means of the posts 30 and 31 to the latter of which is secured an ex-

tension frame 32 that provides a support for the hopper 33 and endless conveyor 34 which is disposed under the discharge end of the conveyor 17 to receive material therefrom, the outer end of the conveyor 34 being adjustable in a vertical plane as by means of the cable 35 which moves over a suitable drum 36 controlled by means of the hand lever 37.

10 The conveyor 34 constitutes the cleaning element of the apparatus and comprises end rollers 38 and 39, the roller 38 being supported in adjustable bearings 40 controlled by the bolt 41 so that the slack in the conveyor 34 may be regulated at the will of the operator.

This conveyor also embodies a suitable frame-work 42 in which are supported the idle rollers 43 over which the endless conveyor 34 moves, there being provided an apron 44 at the lower portion of the frame and over which the lower portion of the conveyor 34 moves for catching foreign matter that drops through the conveyor 34. 25 The endless conveyor 34 is formed of a plurality of rods 45 which have portions thereof bent upwardly as at 46 to grasp the adjacent rod 45 to form a sieving surface permitting the foreign material to drop 30 therethrough, where the same may be carried off by the return movement of the endless conveyor.

Supported within the endless conveyor is an agitating member indicated at 47 which is in the form of a hub 48 and radiating arm 49, the arm 49 supporting the rollers 50 which contact with the under surface of the conveyor 34 to move the conveyor 34 upwardly to agitate the beets supported thereon to dislodge dirt or other foreign matter therefrom, which as before stated falls between the rods 45 where the same collects on the apron 44 from where the same is carried rearwardly and deposited 45 in the hopper 33 which is disposed directly under the roller 38.

A hinged closure 51 is supported at the discharge end of the hopper 33, which closure may be operated to discharge the contents of the hopper 33. The discharge end of the hopper 33 is disposed in a plane to permit a vehicle to pass thereunder, so that when the closure 51 is operated, the contents of the hopper may fall into the vehicle which is shown in dotted lines and indicated by the reference character 52.

The power transmitting mechanism also has connection with a drum 53, through the medium of the chain 54 and sprocket wheel 60, suitable means not shown being provided to clutch the sprocket wheel 60 to the drum to wind the cable 12 thereon to accomplish the raising and lowering of a wagon battery which is to be emptied.

65 The clutch mechanism is controlled by

means of the levers 55, which have connection with the clutch mechanisms, as through the operating rods 56.

In the operation of the apparatus, beets are dumped into the hopper 16 from where 70 they fall onto the endless conveyor 17, which is thrown into operation, and moves the beets upwardly where they are discharged onto the conveyor 34. The agitating means now agitates the conveyor causing the dirt 75 or other foreign matter to be dislodged from the beets, the beets passing on towards the outer end of the conveyor 34 where they are discharged into a suitable conveying means.

It might be further stated that due to the 80 construction of the conveyor 34, the dirt or foreign matter falls therethrough onto an apron 44 from where the same is carried into the hopper 33 and discharged in any suitable conveyor.

Having thus described the invention, what is claimed as new is:—

1. In a beet handling apparatus, an inclined conveyor frame, an endless conveyor operating through the frame, a hopper 90 for discharging material onto the lower end of the endless conveyor, an endless conveyor operating adjacent to the upper end of the first mentioned conveyor and adapted to receive material therefrom, means for agitating the second mentioned conveyor to dislodge foreign matter from the material passing over the last mentioned conveyor, and a hopper for receiving the foreign matter.

2. In a beet handling apparatus, a conveyor frame, a platform supported over one end of a frame, a hopper housing a portion of the conveyor frame, a conveyor operating within the conveyor frame, inclined members disposed adjacent to the side edges 105 of the conveyor for preventing material moving laterally therefrom, an endless conveyor operating under one end of the first mentioned conveyor to receive material therefrom, and means for receiving material 110 from the last mentioned conveyor.

3. In a beet handling apparatus, an inclined conveyor frame, an endless conveyor operating in the frame, idle rollers for supporting the endless conveyor, inclined members overlying the side edges of the conveyor, a conveyor operating under the upper end of the first mentioned conveyor, the last mentioned conveyor being formed of a plurality of spaced rods to permit material to 120 pass therebetween, means for delivering material to the first mentioned conveyor, and means for receiving material from the last mentioned conveyor.

4. In a beet handling apparatus, an inclined conveyor frame, an endless conveyor operating in the frame, a conveyor disposed under the upper end of the first mentioned conveyor and adapted to receive material therefrom, the last mentioned conveyor em- 130

bodying spaced rods, means for agitating the last mentioned conveyor to cause material to drop therethrough, and means for receiving material from the last mentioned 5 conveyor.

5. In a beet handling apparatus, an inclined conveyor frame, an endless conveyor operating in the frame, means for delivering material to the conveyor, an adjustable 10 sieving conveyor disposed under the upper end of the first mentioned conveyor, and means under the last mentioned conveyor for receiving material therefrom.

6. In a beet handling apparatus, an inclined conveyor frame, rollers carried by the 15

frame, an endless conveyor operating over the rollers, a hopper housing a portion of the conveyor and adapted to deliver material thereto, a sieving conveyor disposed under the upper end of the first mentioned conveyor and adapted to receive material therefrom, and a hopper for receiving material from the sieving conveyor. 20

In testimony that I claim the foregoing as my own, I have hereto affixed my signature in the presence of two witnesses. 25

JAMES A. LYNCH.
